UNITED STATES PATENT OFFICE.

HERMAN PARPERT, OF ST. LOUIS, MISSOURI, ASSIGNOR TO AMERICAN STOVE COMPANY, OF ST. LOUIS, MISSOURI, A CORPORATION OF NEW JERSEY.

WATER-HEATER.

1,278,003.

Specification of Letters Patent. Patented Sept. 3, 1918.

Application filed August 20, 1915. Serial No. 46,475.

To all whom it may concern:

Be it known that I, HERMAN PARPERT, a citizen of the United States, residing at St. Louis, State of Missouri, have invented certain new and useful Improvements in Water-Heaters, of which the following is a specification, reference being had therein to the accompanying drawing.

My invention relates to improvements in water heaters.

The object of my invention is to provide a water heater of the coil type in which there is arranged a burner at the upper and lower ends of the coil so that the heat strikes both the upper and lower ends of the coil and more quickly heats the water passing through the coil.

Another object of my invention is to provide a water heater of this character in which the upper burner is formed as an extension of the lower burner, and the gas is supplied to the two burners through a single mixing tube.

A still further object of my invention is to provide a simple, cheap and more effective burner adapted to be used in combination with a coil water heater, and having certain details of structure and combination of parts hereinafter more fully set forth.

In the accompanying drawings,

Figure 1 is a side elevation of the heater showing one portion thereof open, and showing the coil and burner in vertical section.

Fig. 2 is an enlarged vertical sectional view partly broken away and taken at right angles to Fig. 1.

Fig. 3 is an enlarged perspective view of the burner showing the burner cap removed and showing the gas supply for the burners.

Referring now to the drawings, 1 represents the casing which is of the usual structure formed of two sections 2 and 3 hinged together at 4, and whereby access may be readily had to the coil as fully shown in Fig. 1 of the drawings. The two sections of the casing 2 and 3 are preferably provided with an inner lining 4, which is spaced from the outer casing and which extends approximately from the lower end of the coil to the upper end of the coil so that the excessive heat therefrom will not come in direct contact with the outer casing, and therefore, will not warp or disfigure the enamel on the outside of the outer casing.

The coil 5 enters through the lower end

of the casing at a point 6, and extends upwardly in a conical form and passes outwardly from the casing at the point 7. Extending across the upper end of the coil is a plate 8 which is adapted to deflect the frame from the upper burner and cause it to spread out and engage the convolutions of the upper end of the coil. While I have shown the coil 5 within the casing, it will be understood that the same could be in the form of a thin double wall cylindrical member forming a vertical "water column," and in the claims for convenience, I have used the word "water column" which would cover the coils.

While I have shown this coil arranged in a conical form, it will be understood that the same could be arranged in a cylindrical form without departing from my invention. The burner 9 is arranged concentrically within the casing, and has its lower face flush with the lower face of the casing and is supported therein by a bracket 10 carried by the lower end of the casing which extends inwardly, and is provided with a slot 11 through which the ear 12 passes, and passing through the ear is a cotter-pin 13 which engages the lower face of the bracket 10 and supports the burner in a horizontal position. By this arrangement it will be seen that the burner is removably supported and can be replaced or removed for cleaning when desired.

The burner, as shown, is of a ring-like form, forming the trough 14 which is closed by the removable burner head 15, provided with the opening 16 through which the gas passes and at which point it is burned. One side of the ring of the burner has a downwardly extending tube 17 which communicates with the trough 14 and by means of which gas is supplied to the trough 14 and travels around and is discharged through the opening 16 in the burner head around its entire periphery. The tube 17 is provided with a set screw 18 by means of which the mixing tube 19 is secured therein. The mixing tube extends downwardly and has a flared lower end 20 provided with a usual shutter, and a gas supply pipe 21 enters the flared end of the tube 19 and is controlled by the valve 22 as fully shown in Fig. 3 of the drawings. The ring-like burner has extending inwardly the passages 23 and 24 which communicate with a centrally ar-

ranged upwardly extending lip 25 which has secured therein an upwardly extending elongated tube 26 which has an open upper end 27 at a point a short distance below the deflecting plate 8. This burner tube 26 is supplied with gas from the trough 14 through the passages 23 and 24, and whereby the ring-like burner supplies the center burner with gas and but a single gas supply is required.

While I have shown and described this specific means of forming two burners with a central burner connected to the main burner by the transverse passages 23 and 24, it will be understood that the same could be varied without departing from my invention.

By having the burner of the ring-like form, it will be seen that air is supplied through the center of the burner and also around its outer periphery so that the necessary air is supplied to the burner head to cause the perfect combustion of the gas as it passes from the opening 16.

25 By the construction herein shown and described it will be seen that the coil is heated at its lower end by the burner 15, and the additional burner 26 heats the upper end of the coil and the deflector plate 8 prevents the heat from the upper burner from passing directly upwardly thus retarding it and causing a more thorough heating of the upper end of the coil.

Having thus fully described my invention what I claim and desire to secure by Letters Patent is:

1. A water heater comprising a casing, a water column therewithin, a main burner for the lower end of the water column and 40 formed of a ring-like member having inwardly extending passages communicating with the burner, and a second burner supported by the inwardly extending passages and receiving its fuel supply from the main 45 burner, the second burner extending upwardly within the water column and a baffle plate at the upper end of the water column.

2. A water-heater comprising a casing, a lining therefor spaced apart from the casing, the said casing and lining formed in two parts and hinged together, a tubular water column extending upwardly inside of

the said lining, a main burner for the lower end of the water column formed of a ring-like member, a second tubular burner supported by the main burner and receiving its fuel supply therefrom, the said tubular burner extending upwardly within the water column and having its upper end below the upper end of the water column and a baffle plate arranged at the upper end of the water column and directly above the upper end of the tubular burner.

3. A water heater burner comprising a main burner formed of a ring-like member 65 for the lower end, of a water column, inwardly extending passages communicating with the burner and an upwardly extending tube carried by the said passages and forming a second burner and receiving its fuel 70 supply from the main burner through the passages, the second burner for the interior of the column.

4. A water heater burner comprising a main burner formed of a ring-like member 75 for the lower end of the water column and having an open upper end, a removable burner head closing the ring-like main burner, inwardly extending passages communicating with the main burner, an upwardly extending nipple carried by the said passages and communicating with the same, an upwardly extending tube supported by the nipple and forming a second burner receiving its fuel supply from the main burner 80 through the passages and opened at its upper end, the second burner for heating the interior of the water column.

5. A water heater comprising a water column, a burner therefor, said burner comprising a main burner for the lower end of the water column, inwardly extending radial passages communicating therewith, a second burner receiving its fuel supply from the said inwardly extending passages, said 90 second burner extending upwardly within the water column.

In testimony whereof I hereunto affix my signature in the presence of two witnesses.

HERMAN PARPERT.
